UNITED STATES PATENT OFFICE.

JOHN BURKHARDT, OF NEW YORK, N. Y.

WIRE SCREEN, &c.

SPECIFICATION forming part of Letters Patent No. 378,416, dated February 21, 1888.

Application filed September 19, 1887. Serial No. 250,049. (No model.)

To all whom it may concern:

Be it known that I, JOHN BURKHARDT, a citizen of the United States, and a resident of New York, in the county and State of New York, have invented a new and useful Method 5 of Construction of Wire Screens; and I do hereby declare that the following is a full, clear, and exact description thereof, reference being had to the accompanying drawings, and to the letters of reference marked thereon.

In the drawings, Figure 1 represents a transverse central section of a spheroidal body or globe, through which four holes are shown around its center at equal distances apart. 15 Fig. 2 represents the same with a piece of wire or rod inserted through it at two of the holes therein. Fig. 3 represents a sunken bed or die plate, the concavity of which corresponds in size and shape with one-half of the 20 dimensions of the globe and wire represented in Fig. 2, taken longitudinally thereof. Fig. 4 represents a central longitudinal vertical section of the die-plate shown in Fig. 3, with its counterpart, with the globe and wire shown in Fig. 2 placed between them in position to be acted upon by the operation of the dies, and a tool to be used with them. Fig. 5 represents the wire or rod shown in Fig. 2 in the 25 form conferred to it by the action of the tool referred to, after it is inserted through the globe and has been removed from the dies; also shows a transverse section of a transverse wire or rod within the globe, occupying the 30 position as in a finished screen.

This invention consists in a method of forming wire screens and similar articles, and in the production of a screen composed of a series of straight wires or rods, a series of transverse bent wires or rods, and hollow perforated 35 bodies or covers, each of which includes a single joint or intersection of a straight and a bent wire at the bend thereof, as herein more fully described:

This improvement is additional to that described in my application filed in the Patent 40 Office and now pending examination, as it obviates the forming of slits or slots, which had to be opened to receive the series of transverse wires, which had to pass through the openings 45 within the globular joint-covers.

In the drawings, A denotes the hollow spheroidal joint-cover.

B denotes one of the wires or rods which,

for the purpose of definiteness of description, may be termed one of the "longitudinal" series or kind. 55

C denotes a transverse sectional view of one of the wires which may be denominated as of the "vertical" kind or series.

The rods B and C cross each other within the globular or other shaped cover A, and to allow them to pass across each other within the small dimensions of the joint-covers A, in the openings of which they closely fit, and to occupy the same plane in the screen when finished, one of the series of parallel rods or wires 60 is bent laterally, as shown in Fig. 5. The bending is done while they are within their respective joint-covers A and held between the die-plates D E, a hole, a, being formed 65 through the upper plate, D, through which a suitable blunt tool can be inserted and pass through one of the holes x of cover A to receive a stroke of a hammer or the action of a press; and when the rod or wire B and its 70 joint-cover A are removed from the die-plates the cover A is turned on its axis the one-fourth of a revolution, whereby the bent portion of the wire is removed from the direct line of passage of the transverse wires or rods 75 C, that they may pass through the covers A, as shown in Fig. 5.

Having described my improvement in wire screens and similar articles and the method of 80 making the same, I claim—

1. The above-described method of forming wire screens and similar articles, which consists in inserting the longitudinal wire through a hollow perforated body or joint-cover, then producing a bend of said wire within the interior of said body, and then passing the transverse wire through other perforations of the body and through the bend of the longitudinal wire therein, as set forth. 85

2. The wire screen consisting of a series of straight wires or rods and a transverse series of bent wires, in combination with the covers A, each of which includes a single joint or intersection of a straight and a bent wire at the bend thereof, substantially as and for the purpose set forth. 90

September 8, 1887.

JOHN BURKHARDT.
